UNITED STATES PATENT OFFICE

172,502

GAME BOARD

Ralph L. Hovey, Bethel, Kans.

Application July 3, 1952, Serial No. 20,456

Term of patent 7 years

(Cl. D34—5)

To all whom it may concern:

Be it known that I, Ralph L. Hovey, a citizen of the United States, residing at Bethel, in the county of Wyandotte and State of Kansas, have invented a new, original, and ornamental Design for a Game Board, of which the following is a specification, reference being had to the accompanying drawing forming a part thereof.

Fig. 1 is a plan view of a game board, showing my new design, and

Fig. 2 is an edge view thereof.

The drawing is lined for contrasting colors.

I claim:

The ornamental design for a game board, as shown and described.
